FREDERICK W. LYLE, OF WILKINSBURG, PENNSYLVANIA, ASSIGNOR TO WESTINGHOUSE ELECTRIC & MANUFACTURING COMPANY, A CORPORATION OF PENNSYLVANIA

SOUND REPRODUCING DEVICE

Application filed September 18, 1929. Serial No. 393,405.

My invention relates to sound-producing devices such as radio receivers and phonograph reproducers.

It is an object of my invention to supply energy to a sound-producing device from a source of periodic current without causing a hum corresponding to said periodicity.

It is a further object of my invention to provide an arrangement in which a filter, which removes the fluctuation from rectified alternating current less completely than has heretofore been regarded as necessary in order to eliminate the hum, will suffice for its removal.

15 Vacuum tubes have been energized from alternating-current sources before. One way of doing this is to insert a rectifier and a filter between the source and the tubes. If the tubes are in a receiving set or in an 20 amplifier belonging to a sound-producing device to avoid producing a hum has heretofore required that the filter be expensive, bulky and heavy.

When the hum is incompletely eliminated, 25 the quality of the speech or music is unsatisfactory.

I propose to supplement a filter, which would otherwise be insufficient, by impressing upon the voice coil of the loud speaker a 30 current fluctuation of correct intensity and phase to compensate the fluctuations in the magnetic field resulting from the fluctuations in the filtered current. The force exerted upon the diaphragm being the result of the 35 interaction of the current in the voice coil with the field produced by the main coil, a fluctuation in one can be offset by a corresponding and opposite fluctuation in the other.

40 It is an object of my invention to obtain from the current fluctuations in the field coil corresponding fluctuations in the potential of the grid of one or more tubes in the amplifier, thereby controlling the output current of the amplifier, which passes through the voice coil.

Other objects of my invention and details of the construction will be clear from the following description and accompanying drawing in which:

The figure is a diagrammatic view of the apparatus and connections.

The source 1 of alternating current supplies, through a transformer 2, the current for heating the filament 3 of a vacuum tube 4. 55 This tube is shown as of the type having an indirectly heated cathode 5, but any of the expedients for preventing current fluctuations in the filament from producing corresponding fluctuations in the output of the 60 tube may be employed instead of the indirectly heated cathode, if preferred,

The source 1 is connected to a rectifying device which, as illustrated, includes rectifiers 7 arranged in the form of a Wheatstone 65 bridge. It is not essential to my invention that this particular arrangement of rectifiers be used. Any rectifying arrangement producing an output from each half of the alternating-current cycle is preferable to rectifying arrangements yielding an output from 70 only one-half of each cycle, but the half-cycle rectifiers may be used if desired.

The output terminals of the rectifier are connected to a filter which, as illustrated, includes an inductor 8 in one side of the line and a plurality of condensers 9 across the line at each terminal of the inductor. A more elaborate filter may be used, comprising several inductors in series, with a condenser in 80 shunt between each inductor and the next, but with the invention herein described, it is believed that a filter comprising only the three reactors illustrated will prove sufficient for all ordinary situations. 85

The output terminals of the filter are connected to the field winding 11 of a loud speaker of the electrodynamic type. The field winding is in shunt to the plate circuit 90 of the vacuum tube 4. This circuit includes the cathode-anode space of the tube and, in series therewith, the voice coil 12 of the loud speaker, to which the diaphragm 13 is mechanically connected. The cathode of the tube 4 is connected, at 14, to the main leads from the filter to the field coil 11 and the voice coil 12 is connected, at 15, to the other lead from the filter to the field coil. Thus, 95 the connections from the filter to the branch 100

points 14 and 15 are a common supply for the field coil and the plate circuit.

The grid 16 of the tube 4 is connected to the cathode thereof through the secondaries 17 and 18 of two transformers 19 and 20, respectively. Any desired signal voltage is impressed upon the secondary 17. The means for doing this is indicated in the drawing by a rectangle marked "signal source". This is intended to stand for the input coil of a receiving set, the pick-up coil of an electric phonograph or any other source of signal-controlled current. It may also represent the output of an amplifier by which the signal energy has been so increased that it will effectually control the tube 4. Similarly, the tube represented at 4 may, if preferred, instead of delivering energy directly to the voice coil, deliver energy to the input of an amplifier comprising one or more additional tubes, the last of which delivers energy to the voice coil. With such additional amplification, the potential delivered by the secondary 18 need not be as great as required in the system as illustrated.

The primary 21 of the transformer 20 is included in one of the leads from the filter to the field coil. The coupling in this transformer is rendered adjustable in any desired way. The adjustable connector 22 which determines what portion of the inductor 18 shall be shunted by the adjustable condenser 23, provide means for additional control of the phase and amplitude of the potential fluctuations on the grid 16.

In the operation of the device, alternating current is delivered by the source 1 and changed by the transformer 2 to the potential best adapted for the filamentary heater 3. The cathode 5 is heated thereby and supplies electrons for the space current in the tube 4.

The output of the alternating-current source 1 is also delivered to the rectifier 7 and rectified current is thus delivered to the filter 8-9. The pulsating current is smoothed to a certain extent by this filter and the current delivered thereby to the field coil 11 is direct current with a relatively small periodic fluctuation superposed thereon. Resulting periodic fluctuations occur in the magnetic field across the air gap in which the voice coil 12 is located. If the current in the voice coil were steady, there would result a corresponding periodic mechanical force, acting upon the diaphragm 13.

The current in the coil 12 varies in accordance with the signal, but it also varies in accordance with the potential impressed upon the grid 16 by the secondary 18 of the transformer 20. This variation of the grid potential is produced by the fluctuations in the primary 21. The direct current is without effect upon the secondary 18.

The amplitude of the fluctuation superposed on the direct current, the tightness of

coupling in transformer 20 and the position of the adjustable contact 22, together, determine the amplitude of the potential delivered to the grid 16 by the secondary 18.

The adjustment of the coupling and of the number of turns in the secondary may not of itself be sufficient to insure the complete absence of hum, because the fluctuations in the current in the coil 12 may not have the correct phase relation to the fluctuations in the magnetic field in which this coil is located. To further control this phase relation, the adjustable condenser 23 is provided. The circuit including a portion of the secondary 18 and the condenser 23 is so designed that its resonance frequency is very different from the frequency of the periodic fluctuation in the primary 21. Overemphasis of the natural frequency of this circuit is thus avoided.

The changes in potential upon the grid 16 induced by changes in current in the coil 21 are correlated to the changes in current in the field coil 11 and, therefore, to the changes in intensity in the magnetic field in which the coil 12 is located. The changes in potential upon the grid 16 control the changes in current in the voice coil 12 and, therefore, control the mechanical force upon said coil. The adjustments of the coupling, of the terminal 22 and of the condenser 23 are so chosen that the phase of the changes of current in the coil 12 coincide with that of the changes in the magnetic field but are opposite in sense.

The tendency of one change to increase the mechanical force upon the diaphragm is, therefore, compensated by the tendency of the other change to diminish it. Coned adjustment will make the compensation complete. The force exerted upon the diaphragm is thus made independent of the fluctuations in the current delivered by the filter. Since the action of the filter makes these fluctuations small compared to the magnitude of the direct current, any difference in wave form between said fluctuations and the corresponding changes in the current in the voice coil 12 will produce only very small forces acting upon the diaphragm and, therefore, will give rise to no noticeable hum.

When no signal is impressed from the device 18, there will be silence, because the fluctuations in the output of the filter are so nearly completely compensated that they do not move the diaphragm enough to produce an audible sound. When signals are received from the device 18, the change they cause in the output current from the tube 4 is characteristic of the signals and will in no way disturb the compensating action described above. Consequently, no interference with the correct action of the means for preventing hum will arise from the presence of signals.

If extraordinary loud signals are received so that the tube 4 operates beyond the straight-line part of its characteristic, some slight hum might come through which would otherwise be compensated, but this can occur only when the signals are very loud and, therefore, only when the hum will be completely masked thereby.

Many variations of details of the construction will occur to those skilled in the art and the absence of any specific description thereof herein is not intended as a limitation. The only intended limitations are those required by the prior art or indicated in the claims.

I claim as my invention:

1. In combination, an electrodynamic loud speaker having a field coil and a voice coil, a vacuum-tube amplifier having a grid circuit and a plate circuit, a common source of current supply connected to said plate circuit and field coil, the voice coil being in series in said plate circuit and the field coil in shunt thereto and a transformer coupling said common connection to said grid circuit.

2. In combination, an electrodynamic loud speaker having a field coil and a voice coil, a vacuum-tube amplifier having a grid circuit and a plate circuit, a common source of current-supply connected to said plate circuit and field coil, the voice coil being in series in said plate circuit and the field coil in shunt thereto and a transformer coupling said common connection to said grid circuit, and means for adjusting the phase relation between the voltage impressed by said transformer upon the grid and the fluctuations in current in said common connection.

3. In combination, an electrodynamic loud speaker having a field coil and a voice coil, a vacuum-tube amplifier having a grid circuit and a plate circuit, a common source of current-supply connected to said plate circuit and field coil, the voice coil being in series in said plate circuit and the field coil in shunt thereto, and a transformer coupling said common connection to said grid circuit, means for adjusting the closeness of said coupling and means for adjusting the phase relation of the voltage impressed by said transformer upon the grid and the fluctuations in current in said common connection.

In testimony whereof, I have hereunto subscribed my name this 30th day of August, 1929.

FREDERICK W. LYLE.
